UNITED STATES PATENT OFFICE.

OSCAR S. FIELD, OF ELIZABETH, NEW JERSEY, ASSIGNOR TO HALL SWITCH & SIGNAL CO., A CORPORATION OF MAINE.

INTERLOCKING RELAY.

1,279,681.

Specification of Letters Patent. Patented Sept. 24, 1918.

Application filed June 27, 1916. Serial No. 106,162.

To all whom it may concern:

Be it known that I, OSCAR S. FIELD, a subject of the King of Great Britain, and a resident of the city of Elizabeth, county 5 of Union, and State of New Jersey, have invented a certain new and useful Interlocking Relay, of which the following is a specification.

My invention relates to certain new and 10 useful improvements in interlocking relays, being more specifically applicable to alternating current relays or any relay of the type that employs a rotatable or partly rotatable spindle in its operation.

15 The invention consists specifically of improved means of interlocking the two sides of the relay in a simplified manner, which gives a far more rugged and simple construction than has heretofore been used.

20 Other improved features of this device will be more specifically described in the accompanying claims.

Figure 1. shows a front elevation of one form of Vane type relay employing my invention.

Fig. 2. is a transverse section of the relay taken through the line A.

Fig. 3. is a diagrammatical view of the 25 relative positions of the interlocking members when both sides of the relay are energized.

Fig. 4. is a diagrammatical view of the relative positions of the interlocking members when both sides of the relay have been 30 deenergized in due sequence.

Fig. 5. is a diagrammatical view of the 35 interlocking cams, showing their relative positions when both sides have been deenergized, and the first side to be deenergized has again become energized.

Referring to the various figures and employing like numerals throughout, the construction and operation of the device is as follows:

40 Fig. 1. shows one form of a typical Vane type relay consisting of a base 1 which carries split phase operating magnets 2 and 3 mounted thereon as shown. Between the poles of these magnets are inductively 45 operated, metallic segments 4 and 5, which are mounted upon spindles 6 and 7 in such a way that they may pass freely between the poles of the magnets 2 and 3. The magnets are arranged in such a manner that

upon magnet 2 being energized with alternating current, it will cause segment 4 to rotate about the spindle 6 in a clockwise direction, and upon the energization of magnet 3 it will rotate segment 5 about the spindle 7 in a counter clockwise direction. 55

The spindles 6 and 7 are carried in suitable bearings 8, which are mounted upon base 1. Attached to the spindles 6 and 7 as shown, are crank plates 9 and 10. Insulated contact finger bars 11 and 12 are 60 pivotally mounted to the base 1 by means of pivot 13, in such a manner that they may rotate about the pivot 13 and thereby operate the front contacts 14 and 15 and the back contacts 16 and 17 of their respective 65 sides. From each contact finger bar a lever 18 is projected back and connected by means of links 19 and 20, to pivots 21 and 22 on the crank plates 9 and 10.

70 It will, therefore, be seen, referring to Fig. 1. that when the magnets are deenergized, by means of the action of gravity, the segments will tend to assume a position as shown by segment 5, thereby closing the back contacts 17. Upon the energization of one or the other of the magnets, the segment 75 will assume a position as shown by segment 4, thereby opening the back contacts 16 and closing the front contacts 14.

All of the contacts 14, 15, 16 and 17 are 80 mounted on a suitable insulated base 23.

85 Each of the segments 4 and 5 carry suitable stops 24 and 25 rigidly mounted thereon. Upon the shafts 6 and 7 are mounted interlocking members 26 and 27, in such a 90 manner as to be free to rotate upon their respective shafts and so located that they will engage with stops 24 and 25 carried by the segments. The operation of the relay is as follows:—

95 When both sides of the relay are energized, the segments 4 and 5 will both be in their upper position as indicated by segment 4 in Fig. 1, thereby retaining all the front contacts 14 and 15 closed, and the interlocking members 26 and 27 will assume the positions shown in Fig. 3, due to the action of gravity, and will be resting against their respective stops 24 and 25.

100 When magnet 3 becomes deenergized the segment 5 will rotate in a clockwise direction due to gravity, opening its front contacts 15 and closing its back contacts 17.

The stop 25 on segment 5 will engage the interlocking cam 27 and move it to the position shown in Fig. 1.

When magnet 2 becomes deenergized the segment 4 will rotate in a counter clockwise direction, due to gravity, opening its front contacts 14.

The stop 24 will engage the interlocking member 26 and rotate it to the position shown in Fig. 4.

It will be seen that face 29 of member 26 will engage with the face 30 of member 27, thereby interlocking this side of the relay and preventing the segment 4 from completing its stroke and closing its back contacts 16.

Should the magnet 3 now again become energized, the segment 5 will be rotated in a counter clockwise direction, opening its front contacts 15 and carrying its stop 25 to the position shown at 25 in Fig. 5.

However, it will be seen that interlocking cam 27 is still retained in its interlocking position, owing to the fact that the point 31 of cam 27 is latched behind the projection 32 of cam 26.

Upon the reenergization of the magnet 2, the segment 4 will be rotated in a clockwise direction, thereby closing its front contacts 14 and carrying its stop 24 to the position shown in Fig. 1, the interlocking member 26 following the stop 24 due to the action of gravity. It will be seen that this will now release the interlocking member 27, and that this member will also rotate by means of gravity until it engages with its stop 25.

The relay has now reassumed its normal energized condition, having passed through a complete cycle of operation. It is obvious that this cycle of operations will be similar whichever magnet is deenergized first.

While I have shown one specific type of relay and method of applying my invention to the same, I do not wish to be restricted to this specific type of relay and particular construction, as it is obvious that the invention is susceptible to a variety of modifications.

Having described my invention what I claim as new and desire to secure by Letters

50 Patent is:-

1. In a relay, the combination of rotatable shafts, means for causing the partial rotation of said shafts to control electric circuits, and members pivotally mounted upon said shafts in operative relation and adapted to restrict the movement of one of said shafts according to their sequence of operation.

2. In a relay, the combination of rotatable shafts, means for causing the partial rotation of said shafts to control electric circuits, and interlocking means between the shafts, consisting of double arcuate faced members

so pivotally disposed as to limit the movement of one of said shafts according to their sequence of operation.

3. In a relay, the combination of rotatable shafts, means for causing the partial rotation of said shafts to control electric circuits, interlocking members pivotally mounted upon said shafts in operative relation and adapted to restrict the movement of one of said shafts according to their sequence of operation, and means associated with the members for retaining the members in the interlocked position after the return of one of the shafts.

4. In a relay, the combination of two rotatable shafts, means for causing the partial rotation of said shafts to control electric circuits, and two members pivotally mounted in operative relation, each of which is adapted to be thrown into operative position by movement of one of the shafts and to operate when in such position, to restrict the movement of the other shaft.

5. In an interlocking relay, the combination of two electrically operated devices operating to control electric circuits, two members cooperatively related and pivotally mounted in free relation to the operated devices having coacting arcuate faces so disposed as to restrict the full movement of one or the other of the said electrically operated devices in accordance with their sequence of operation, and means associated with the operating device to control the operation of said members.

6. In a relay, the combination of two rotatable shafts, means for causing the partial rotation of said shafts to control electric circuits, two members pivotally mounted in operative relation, each of which is arranged to be thrown into operative position by movement of one of the shafts and to operate when in such position, to restrict the movement of the other shaft, and means on the members for retaining the same in the interlocked position after the return of one of the shafts.

7. In an interlocking relay, the combination of two electrically operated devices operating to control electric circuits, two pivotally mounted members having coacting arcuate faces so disposed as to restrict the full movement of one of the said electrically operated devices and adapted to be operated by said devices, and means associated with the members for retaining the members in the interlocked position after the return of one of the devices.

In testimony whereof I have signed my name to this specification.

OSCAR S. FIELD.
